UNITED STATES PATENT OFFICE.

JOHN FRANKLIN RICHARDSON, OF MONTREAL, QUEBEC, CANADA.

ELECTRIC-LINE-TAPPING CONNECTOR.

1,027,279.

Specification of Letters Patent.

Patented May 21, 1912.

Application filed January 15, 1908. Serial No. 472,486.

To all whom it may concern:

Be it known that I, JOHN FRANKLIN RICHARDSON, a subject of the King of Great Britain, and resident of 214 Mance street, 5 in the city and district of Montreal, in the Province of Quebec, in the Dominion of Canada, have invented certain new and useful Improvements in Electric-Line-Tapping Connectors; and I do hereby declare that 10 the following is a full, clear, and exact description of the same.

The invention relates to improvements in electric line tapping connectors, as described in the present specification and illustrated in 15 the accompanying drawings that form part of the same.

The invention consists essentially in arranging one or more flexibly connected hooks in combination with a staff or pole.

20 The object of the invention is to provide a convenient means of reaching the electric current conducting wires of telephone, telegraph or power services between stations, to devise a connector that may be attached to 25 the wires no matter in what position the said wires are arranged, and generally to simplify the construction of such devices.

In the drawings, Figure 1 is a perspective view of a telegraph line and of the device 30 with the contact hooks in position. Fig. 2 is a perspective detail of the invention showing the pole broken away.

Like numerals of reference indicate corresponding parts in each figure.

35 Referring to the drawings, 1 is the staff or pole preferably formed of a light bamboo stick and in sections joined by ferrules 2, though it must be understood that this staff or pole may be made of any suitable material, naturally a light and wood material being the most desirable.

40 3 is a ferrule encircling the top end of the staff 1 and surrounding the socket 4.

45 7 is a hook here shown as formed of flat wire material and inverted V-shaped, though it may be of any suitable contacting material in any desired shape. Said hook 7 is rigidly secured to the ferrule 3 and stands out from the periphery thereof and extends 50 to and is connected with the terminal 8, said terminal being formed with the usual contact screw 9 and plate 10.

55 12 is a contact plate preferably in vertical alinement with the contact 9 having the contact screws 13 and 14, the contact screw 13

being electrically connected by the wire 15 to the contact 9 therefore electrically connecting the contact plate 12 with the hook 7.

16 is a wire connecting the contact screw 14 and therefore the hook 7 to the portable 60 instruments.

17 is a contact plate in circumferential alinement with the contact plate 12 having the double screw contacts 18 and 19, the screw 19 being connected to the portable instruments by the wire 20.

21 is a contact plate slightly below the ferrule 3 on the staff 1 and having the screw contacts 22 and 23 secured therein, the screw contact 23 being connected to the contact 70 19 by the wire 24.

25 is a hook similarly formed to the hook 7 having a contact shank 26 and screw contact 27 in said shank, the screw contact 27 being electrically connected to the screw 75 contact 22 by the slack wire 28.

29 is a rope of suitable non-conducting material and secured to the loose hook 25, said rope extending down the center of the bamboo staff or pole and further extending 80 out through a suitable opening 30 in the wall of said staff or pole consequently by drawing on said rope, the hook 25 is pulled into the socket 4.

In the use of this device, it is preferable 85 for the sake of portability to have the pole in two or more sections so that the said pole can be made long enough to reach the telephone or other wires, the hole through which the rope extends in the wall of the 90 pole is, of course, in the uppermost section so that it may be readily caught in the hand in order to bring the loose hook 25 back in its socket after it has been removed from the wire. One of the hooks is first 95 caught on to one of the wires and then the other, the loose hook pulling out with it the rope 29, consequently it matters not in what particular position the second wire is, that is to say, whether it is strung in the 100 same plane or in a lower or higher plane, the said loose hook will reach it, if it is not beyond the length of the slack wire 28 and of course it may be here noted that the said slack wire may be made any desired 105 length.

It must be understood that without departing from the spirit of the invention, the hooks may be arranged in any suitable manner and also the electrical connections, that 110

is to say, both hooks may be flexibly arranged and wiring may be direct from the hooks to single contacts or in fact several incidental changes may be made as long as 5 the salient features of the invention are adhered to.

What I claim as my invention is:

In an electric line tapping connector of the kind having a loose hook and a fixed 10 hook, a hollow non-conducting multiple-section pole having the fixed hook rigidly secured to the tip of the top section of said pole, a non-conducting rope having the loose hook at the outer end thereof and extending 15 through said top section and out through a hole near the bottom of said top section, a pair of terminal plates secured to the exterior of said top section near the bottom thereof, a terminal plate secured to the ex-

terior of said top section near the top thereof, a slack wire electrically connecting said loose hook and said top terminal plate, a wire electrically connecting said top terminal plate and one of said lower terminal plates, a wire electrically connecting said 20 fixed hook and the other of said lower terminal plates, and a wire leading from each 25 of said lower terminal plates to an electrical instrument.

Signed at the city and district of Montreal, in the Province of Quebec, in the Dominion of Canada, this 12th day of January, 1909.

JOHN FRANKLIN RICHARDSON.
